Primary Examiner — Sheryl Lane*Assistant Examiner* — Samantha Lynne Brodowski(57) CLAIM

The ornamental design for a crossbody bag, as shown and described.

DESCRIPTION

FIG. 1 is a perspective view of a crossbody bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the crossbody bag where the crossbody bag is in a configuration of use; and, broken lines depict the cut line of the enlarged portion and form no part of the claimed design.

1 Claim, 10 Drawing Sheets
